UNITED STATES PATENT OFFICE.

ROBERT W. KING, OF TORONTO, ONTARIO, CANADA.

FURNACE.

1,379,448.

Specification of Letters Patent. Patented May 24, 1921.

Application filed November 1, 1919. Serial No. 334,912.

To all whom it may concern:

Be it known that I, ROBERT W. KING, of the city of Toronto, in the county of York, Province of Ontario, Canada, have invented 5 certain new and useful Improvements in Furnaces, of which the following is a specification.

The object of this invention is to provide improved means for the burning of sub-bituminous or lignite coal or other fuels of a 10 like nature.

In ordinary practice when such fuel, especially in its broken condition or "slack" form, is placed on the surface of other ignited fuel it tends to dampen the same and 15 reduce the temperature of the combustion chamber.

The new charge heated from below throws off gas from the surface which passing into 20 the cooled combustion chamber, is not consumed but passes away in the form of smoke. In the course of time, as combustion commences below, this escaping gas ignites often with explosive violence and an intense fire 25 is created rapidly exhausting and wasting the fuel. I overcome the above difficulties by burning the fuel in a manner made possible by the improved construction herein-after fully described and shown.

30 Briefly the method employed is to burn the fuel as largely as possible by ignition from the upper surface downward and at the front of the furnace until it is largely converted into red hot cinders which are 35 then passed to the rear of the furnace to complete their combustion, partly by surface combustion and partly with the aid of air admitted into the fuel bed. This process requires that the fuel at front of the furnace 40 be supported on a substantially imperforate fuel supporting surface, that a suitable support for partly consumed fuel be provided at the back of the furnace, that air, preferably warmed, be admitted above 45 the fuel at the back of the furnace and caused to travel forwardly over the fuel, that air be admitted under close regulation into the body of fuel at the back of the furnace and that provision be made for the 50 discharge of ashes from the fuel support at the back of the furnace be provided.

The apparatus I have devised for this pur-

pose is hereinafter specifically described and illustrated in the accompanying drawings in which—

55 Figure 1 is a vertical longitudinal section of a rectangular furnace constructed in accordance with my invention;

Fig. 2 a front elevation of the same partly in section;

Fig. 3 a plan view of the same, partly broken away and partly in section;

Fig. 4 a front elevation of the rock shaft of the shaker mechanism;

Fig. 5 a detail in side elevation of one of 65 the fixed grate bars applied to a cylindrical furnace;

Fig. 6 a modification of my invention applied to a cylindrical furnace; and

Fig. 7 a cross section on the line *a—b* in 70 Fig. 6.

In the drawings like numerals of reference indicate corresponding parts in the different figures.

Referring particularly to Figs. 1 to 5, 1 75 is the wall of the furnace, of any suitable material and construction, 2 the combustion chamber or upper part of the fire pot, and 3 the ashpit. The fuel supporting surface is formed in two parts 4 and 5. The part 80 4, or primary fuel supporting surface is located adjacent the fuel door 6 and the part 5, or secondary surface at the rear of the furnace. The part 4 is substantially imperforate, whereas the part 5 has suitable 85 apertures formed therein through which air from the ashpit may be allowed to pass to help sustain combustion of the fuel lying thereon.

At the top of the combustion chamber 90 over the primary fuel supporting surface is located the smoke outlet 7, preferably as close as possible to the fuel door 6. To provide air for the surface combustion of the fuel and the gases evolved therefrom it is 95 necessary to admit air into the combustion chamber above the fuel. For this purpose I provide flues or air passages 9, preferably so located as to be heated by the heat generated in the furnace. In the preferred arrangement these passages are formed in or on the walls of the furnace as shown. Each air passage has a damper controlled air inlet 11 for the admission of atmospheric air,

and also a damper controlled opening 10 located within the ashpit of the furnace. Each air passage is provided with one or more openings 12 leading into the upper 5 part of the combustion chamber above the fuel level, and also with an opening 13 below the level of the fuel at the back of the furnace.

From the above construction it follows 10 that the fuel burns mainly from above, air being supplied through the openings 12 while the final combustion of the fuel is pushed over to the back of the furnace is effected by air admitted through the openings 13 and by such air as may be admitted 15 into the ashpit to pass through the secondary fuel support 5.

To properly direct the air from the inlets 12 and the products of combustion from the 20 rear of the furnace over the fuel and on the primary fuel support 4, I provide the downwardly and forwardly inclined baffle 8 secured to the top of the furnace just behind the smoke outlet 7.

25 For various reasons it is desirable to raise the primary fuel support 4 above the secondary fuel support 5 so that there is a transverse division between the parts forming a vertical opening 14 through which ashes and 0 clinkers may work into the ashpit. The raising of the fuel support 4 also brings the fuel thereon into better position for the air and hot products of combustion from the fuel at the back of the furnace to flow over 35 its surface on their way to the smoke outlet 7. Preferably the parts overlap as shown in Fig. 1, and the secondary fuel supporting surface 5 slopes toward the front.

The rear edge 15 of the primary fuel 40 supporting surface is preferably downwardly turned to restrict the opening 14 to the extent experience dictates. Also to facilitate the feeding of fuel over the secondary fuel supporting surface 5, the forward part 45 16 of the primary fuel supporting surface 4 is preferably downwardly inclined from the fire door opening as shown in Fig. 1.

In starting a fire in the furnace, it is sometimes desirable to have direct draft 50 from the rear part of the combustion chamber and I therefore provide a damper-controlled outlet 17 over the secondary fuel supporting surface 5. With this opening 55 the smoke pipe 18 communicates, which pipe may be connected by the pipe 19 with the smoke outlet 7.

The secondary fuel supporting surface 5 is preferably arranged to be shaken. In 60 Figs. 1 to 5 I show a preferable arrangement of the grate for use in rectangular furnaces. Stationary grate bars 20 are alternated with movable grate bars 21. The stationary grate bars are supported on the cross bar 22 adjacent the opening 14, while 65 their rear ends are supported on the lower

flange of a channel bracket 23 secured to the rear wall of the furnace. The movable bars 21 slide freely on the cross bar 22, and at their rear ends are pivotally connected with rock arms 24 formed on or secured to 70 a rock shaft 25 suitably journaled in the sides of the furnace. A depending rock arm 26 is also formed on or secured to the shaft 25. A shaker lever shaft 27 is journaled at the front of the furnace and has 75 formed on or secured thereto a depending rock arm 28. The rock arms 26 and 28 are pivotally connected at the opposite ends of a connecting rod 29. A suitable shaker lever 30 is connected in any usual manner 80 to the outer end of the shaft 27. With this arrangement, the shaking of the grate bars may be effected at the front of the furnace as is generally a preferred arrangement, though, of course, any other arrangement of the shaking means may be employed.

It will be noted that each stationary grate bar has a shoulder 31 formed thereon behind the cross bar 22. To remove one of 90 the stationary bars it is necessary therefore to lift its forward end and then draw it forwardly. No accidental displacement is however possible. To remove a movable grate bar, it is necessary to rock the rock 95 shaft 25 farther than is necessary for shaking purposes to bring the rear end of the bar to such a position that it can be lifted from its pivot on the rock arms 24, the upper member of the channel casting 23 normally preventing such lifting action. A removable pin 32 or other stop is provided which ordinarily limits the movement of the shaft 25 by engagement with the rear side of the 100 depending rock arm 26.

To best effect a discharge of clinkers of ashes through the opening 14, the grate bars 20 and 21 are preferably curved concavely at their upper surfaces and are provided with ratchet-shaped teeth 33, the teeth preferably decreasing in size toward the rearward part of each grate bar.

In Figs. 6 and 7 I show a modification of my invention as applied to an ordinary cylindrical hot water heater. The primary 115 fuel supporting surface 4 is shown substantially horizontal, the sloping part 16 shown in Fig. 1 being omitted. The depending part 15 forming the rear edge of this part of the grate also extends more 120 nearly vertically. The secondary fuel supporting surface 5 is shown as formed of a series of rocking bars 34 of ordinary type. These will be arranged to be shaken in any ordinary manner.

The rearward smoke outlet is in this case omitted, the products of combustion all passing up through the forward smoke outlet 7. The air passages 9 remain substantially the same as in the other form of fur- 130

nace shown, but I find it desirable, to make them of a semi-segmental form in plan and locate them one at each side of the rear portion of the grate, the short end rocking 5 bars commonly employed in this form of furnace being therefore omitted.

The operation of the furnace can best be understood from the following description of an actual run. In lighting the furnace, 10 the fire pot was first filled with the fuel up to substantially the level of the lower side of the fuel opening as indicated by dotted lines in the drawings, and a small fire of kindling was started at the rear of the combustion chamber at 8.15 a. m. While all 15 drafts were open, the air for supporting the combustion of the kindling was supplied mainly by the air flues 9 through the openings 12 above the fuel. At 8.22 a. m. the direct damper 17 was closed. By 9.15 a. m. the fire was well ignited and the fire was checked about 10.15 a. m. by partly closing the ashpit and air flue dampers. By 11.15 20 the fire was burning steadily and coal was added at the front of the furnace. Gas was seen to be burning around the air openings 25 12. By 12.15 the fuel at the back of the furnace had become red hot and gas from the coal at the front of the furnace was burning 30 freely.

At 3.00 p. m. the fire was still steady and more coal was added. At 4.30 part of the air flues 9 were closed. At 6 p. m. more coal was added and all the auxiliary air ports 35 were opened. The fire picked up quickly, gas burning at the auxiliary air ports as before. Thereafter the fire was partly checked by closing some of the air flues. At 10 p. m. the fire was banked for the night 40 with coal and the dampers closed.

At 9 a. m., the following morning, the fire was in good condition and picked up quickly when the dampers were opened. By this time it was necessary to get rid of some of 45 the ashes on the rear fuel support and to push the fuel from the front of the furnace to the back, leaving space for fresh fuel at the front, while the hot coals finished their combustion at the rear and maintained a 50 suitable temperature in the combustion chamber for the evolution and ignition of the gases of the green fuel.

In this test it was demonstrated that the admission of air through the auxiliary openings 55 12 and 13 was absolutely essential for complete combustion; that the admission of air from below through the rear fuel support was non-essential; that the admission of air through the space between the two 60 parts of the grate was not detrimental, and in any case was readily controlled by means of the ashpit damper; that the deflecting plate or baffle in the combustion chamber satisfactorily served the purpose of causing 65 the air and heated gases from the rear part

of the furnace to impinge on and thus cause the evolution and combustion of the gases of the green fuel; that the gases evolved burned quietly and thoroughly and without explosions; that flue gas losses were very 70 low and that the efficiency of heat transfer was high.

What I claim as my invention is:—

1. In a furnace the combination of an imperforate primary fuel support; a secondary fuel support behind the primary fuel support; means for admitting air into the body of the fuel on the secondary fuel support; means for supplying air above the fuel at the rear of the furnace; and a smoke outlet 80 at the front of the furnace above the primary fuel support.

2. In a furnace the combination of an imperforate primary fuel support; a secondary fuel support behind the primary fuel support partly underlying said primary fuel support and spaced therefrom to provide an ash discharge; means for supplying air above the fuel at the rear of the furnace; and a smoke outlet at the front of the furnace above the primary fuel support.

3. In a furnace the combination of an imperforate primary fuel support; a secondary fuel support behind the primary fuel support; air supply ducts adapted to be heated 95 by conduction from the furnace walls and communicating with the interior of the furnace at the rear part thereof above the secondary fuel support at points both below and above the fuel level; and a smoke outlet 100 at the front of the furnace above the primary fuel support.

4. In a furnace the combination of fuel supporting means substantially imperforate at the front of the furnace; means for admitting air above the fuel supporting means into the body of fuel at the rear of the furnace; means for supplying air above the fuel at the rear of the furnace; a smoke outlet at the front of the furnace; and means 110 for the discharge of ashes from above the rear part of the fuel supporting means.

5. In a furnace the combination of fuel supporting means substantially imperforate at the front of the furnace; means for admitting air above the fuel supporting means into the body of fuel at the rear of the furnace; means for supplying air above the fuel at the rear of the furnace; a smoke outlet at the front of the furnace; means for 115 the discharge of ashes from above the rear part of the fuel supporting means; and a baffle intermediate of the ends of the furnace adapted to direct air and products of combustion down against the fuel at the 120 forward part of the furnace.

6. In a furnace the combination of fuel supporting means substantially imperforate at the front of the furnace; means for admitting air above the fuel supporting means 130

into the body of fuel at the rear of the furnace; means for supplying air above the fuel at the rear of the furnace; a smoke outlet at the front of the furnace; a damper controlled smoke outlet at the rear of the furnace; means for the discharge of ashes from above the rear part of the fuel sup-

porting means, and a baffle intermediate of the ends of the furnace adapted to direct air and products of combustion down against the fuel at the forward part of the furnace.

Signed at Toronto this 15th day of October, 1919.

ROBERT W. KING.
